Patented May 9, 1922.

UNITED STATES PATENT OFFICE.

SAMUEL WEISSMAN AND RALPH WEISSMAN, OF DETROIT, MICHIGAN.

SIDE THRUST SUPPORT FOR SPRING-BED BOTTOMS.

1,415,068.

Specification of Letters Patent. Patented May 9, 1922.

Application filed February 13, 1922. Serial No. 536,119.

To all whom it may concern:

Be it known that we, SAMUEL WEISSMAN and RALPH WEISSMAN, citizens of the United States of America, residing at Detroit, in the county of Wayne and State of Michigan, have invented certain new and useful Improvements in Side Thrust Supports for Spring-Bed Bottoms, of which the following is a specification, reference being had 10 therein to the accompanying drawings.

This invention relates to a side thrust support for spring bed bottoms of that type employing a plurality of longitudinal and transverse rows of springs secured to and supported at their lower ends on a frame structure that engages the side rails of the bed and at their upper ends connected to each other and to side and end members of the upper frame so as to secure each spring 15 against substantial lateral displacement while permitting free vertical yield thereof.

Our invention aims to provide yieldable supports for the side edges of the upper frame of a spring bed bottom and the supports are arranged to receive any side thrust so that the top frame will be caused to shift in a defined direction, eliminating side swaying without reducing the cushioning effect of such springs of the bed bottom as are 20 brought into action by weights thereon.

Our invention further aims to provide a spring bed bottom with side thrust units which maintain a defined relation between the side edges of the upper frame of the bed 25 bottom and the side edges of the bottom frame so that when the side edge of the top frame is depressed, for instance by being sat upon, the edge of the frame must assume a defined position when returning to normal 30 position.

Our invention further aims to provide side thrust units which will maintain the top frame work or webbing of a bed spring taut and prevent depressed portions because 40 of constant use.

Our invention further aims to provide side thrust supports for a spring bed bottom that may be easily and quickly installed, manufactured at a comparatively small cost, 45 and used without any danger of a mattress or other bed being injured or torn.

Our invention possesses other advantages that may appear as the invention is herein-after described, and reference will now be 50 had to the drawing wherein—

Figure 1 is a diagrammatic plan of a

spring bed bottom with a longitudinal central portion thereof broken away, showing only the side portions of the spring bed bottom;

Fig. 2 is an enlarged plan of the side portion of the spring bed bottom;

Fig. 3 is a side elevation of a side thrust support in accordance with our invention;

Fig. 4 shows views, on a small scale, of a modified form of side thrust support;

Fig. 5 is a perspective view of a portion of one of the members of the side thrust support, and

Fig. 6 is a similar view of a further modification of our invention.

The spring bed bottom shown in the drawings comprises a lower frame 1 that may be made of channel or angle iron, and the side rails 2 of the frame are connected by transverse spring supporting members 3 on which are mounted and suitably secured the lower convolutions of springs 4, said springs having the upper convolutions thereof suitably connected together by members 5 within an upper frame 6 which is held in spaced relation to the lower frame 1 by the expansive force of the springs 4. The upper frame 6 may be made of wire or any suitable material that will afford a substantial edge for the upper portion of the spring bed bottom.

The spring supporting members 3 may be conveniently considered as being in sets with the members of each set connected by longitudinally disposed bars 7 and each bar, intermediate its ends is connected to the rail 2 by an inclined base piece 8, said base piece and said bar being preferably made of metallic straps having the ends thereof bent or twisted for attachment to the members 3 and the rail 2 by rivets or other fastening means. The bar 7 is necessarily set at an angle so that the base piece 8 may extend upwardly at an inclination to the plane of the dropped portions of the spring supports 3.

As an instance of other fastening means, than rivets, we show in Fig. 6 a bar 7^a having hooked shaped end tongues 2^a extending into openings 3^a in the supports 3 and the lower end of the base piece 8 has a tongue 8^a extending into an opening of the bar 7^a. When the supports 3 and base piece 8 are in position, the tongues will hold the parts assembled.

Pivotedly connected to a side wall of the base piece 8, by rivets 9 or other pivotal means, are the lower ends of link members

or pieces 10 and 11, and pivotally connected to the upper end of the link piece 10, by a rivet 12 or other pivotal means is an upwardly supporting piece 13 which is pivotally connected by a rivet 14 or other pivotal means to the upper end of the link piece 11, said link piece being of greater length than the link piece 10 so that the supporting piece 13 may be at an acute angle to the base piece 8. This angle is defined by an inwardly projecting lug 15 struck out from an edge of the supporting piece 13, said lug engaging an edge of the link piece 11 and maintaining said link piece 15 at substantially a right angle to the supporting piece, when considering the normal position of the supporting piece relative to the link pieces. The manner of articulating the pieces 8, 10, 11 and 13 does not interfere with an inward or upward movement of the pieces 10, 11 and 13 relative to the side of the spring bed bottom, but the outward movement of the supporting piece 13 is defined by reason of the lug 15 and the 25 link pieces 10 and 11.

The upper end of the supporting piece 13 is twisted and bent about the top frame 6, as at 16 and when any pressure is brought to bear on said top frame the lowering of 30 said frame is not interfered with, except against excessive inward movement, such movement being limited by the link pieces 10 and 11 swinging downwardly.

Considering the units at the sides of the 35 spring bed bottom, with reference to Fig. 1, it will be noted that the units are tied in such a manner as to compensate for side thrust, it being practically impossible to break down the edge of the spring bed bottom due to constant sitting on the edge, as the top frame is caused to assume its normal position when the top frame is relieved of pressure. The greatest action of the units is apparent when the central portion 45 of the spring bed bottom is subjected to pressure as then the sides of the top frame are supported so that the central depressed portion of the spring cannot carry the sides of the top frame inwardly and upwardly 50 beyond the distance defined by the side thrust supports, but in no instance do these supports interfere with the yielding of the springs in a vertical direction. In other words, the springs may be depressed and the 55 top frame carried downwardly, but the sides of the frame cannot be pulled inwardly or upwardly by reason of the units defining the movement of the sides of the top frame. The top framework or webbing will therefore be maintained stretched and taut with 60 no central sagged portion due to constant use.

In practice we may use only one or two side thrust units at each side of the spring bed bottom, said units being placed where

the spring bed bottom is subjected to the greatest use.

It is obvious that other material may be substituted for the flat or strap material shown for the link pieces 10 and 11, and as an instance of such material we show in Fig. 4 link pieces 17 made of rigid wire having ends bent, as at 18, to be used similar to the rivets, and a piece of wire which 75 forms the outer link piece may be bent to provide an offset lug portion 19 which will serve the same purpose as the lug 15. This is simply an example of various materials and linkage that may enter into our side 80 thrust support, and we do not care to confine our invention to the construction of the spring bed bottom, as our side thrust supports may be applicable to other spring bed bottoms. It may be necessary to make 85 slight changes in the construction of our supporting units, therefore we do not care to limit our invention other than defined by the appended claims.

What we claim:—

1. The combination with a spring bed bottom having an upper frame, a lower frame, supporting members carried by said lower frame, and springs on said supporting members, of side thrust supports at the sides of 95 the spring bed bottom; each side thrust support comprising an inclined base piece carried by the lower frame, an inclined supporting piece connected to the upper frame, and linkage connecting the base and supporting 100 pieces, said linkage causing the supporting piece to swing inwardly when the upper frame is subjected to pressure.

2. The combination set forth in claim 1, wherein the linkage includes two link pieces 105 one of which is normally held at a defined angle by the supporting piece.

3. The combination with a spring bed bottom having an upper frame, a lower frame, supporting members carried by said lower 110 frame and springs on said supporting members, of side thrust units between said upper and lower frames, each unit comprising a bar connecting the supporting members, an inclined base piece connecting said bar to 115 a side rail of the lower frame, link pieces connected to said inclined piece, and a supporting piece connected to said links and to said upper frame, the articulation of said links and said supporting piece being such 120 that said supporting piece is caused to move downwardly and inwardly when said upper frame is subjected to pressure.

In testimony whereof we affix our signatures in presence of two witnesses.

SAMUEL WEISSMAN.
